(57) **CLAIM**

The ornamental design for a topper for bubble solution container, as shown and described.

DESCRIPTION

FIG. 1 is a perspective view of the topper for bubble solution container.

FIG. 2 is a perspective view of the topper for bubble solution container of FIG. 1, with the broken lines shown herein forming no part of the claimed design and showing one environment in which the topper is used.

FIG. 3 is a perspective view of the topper for bubble solution container of FIG. 1, with the broken lines shown herein forming no part of the claimed design and showing another environment in which the topper is used.

FIG. 4 is a front view of the topper for bubble solution container of FIG. 1.

FIG. 5 is a rear view of the topper for bubble solution container of FIG. 1.

FIG. 6 is a left view of the topper for bubble solution container of FIG. 1.

FIG. 7 is a right view of the topper for bubble solution container of FIG. 1; and,

FIG. 8 is a top view of the topper for bubble solution container of FIG. 1.
